HERMAN POTRAFKE, OF ASHFORD, AND ROY N. ALLEN, OF TACOMA, WASHINGTON.

LOWERING CAR FOR INCLINE RAILWAYS.

Application filed November 29, 1924. Serial No. 752,855.

This invention relates to a car of new and improved design intended primarily for moving burden-bearing cars and logging trucks of ordinary construction on incline 5 railway tracks as in logging operations in mountainous country, where it is frequently found economical to haul empty logging cars or trucks up a steep incline for loading, then to lower them with their loads to 10 a railroad on which they are subsequently drawn by locomotive or similar motive power and the object of this invention is to provide a car of this nature that will operate efficiently and that will reduce the 15 wear on the hauling cable to a minimum.

The power supplied by a stationary donkey engine moves the car by means of a two part line or cable at each side of the track between the car and the engine, the cable 20 on one side moving in the direction of the movement of the haul at double the speed of the car, the cable on the other side being at rest.

The car is particularly adapted to incline 25 railways having more or less curvature and changes of grade. The car body is mounted upon a substantial truck placed at or near midway of its length in an appropriate manner to permit vertical and horizontal 30 movement of the ends of the car.

A pony truck, such as is used under ordinary railroad locomotives, is placed under each end of the car to act as a guide to prevent derailment on curves. The object of 35 this construction is to permit the adjustment of the car body with the draft line of the cable eliminating bending of the cable.

On the car body is mounted a sheave of sufficient diameter to carry the moving cables outside the rails of the track. This 40 sheave revolves upon a pin, one end of which operates in a bearing in the bottom of the car body, and for the purpose of greater rigidity and strength extends above the 45 sheave into a bearing within a beam above the sheave, securely fastened at its ends to the car body outside the circumference of the sheave. While this is a preferable construction, any means by which the sheave 50 can be held in secure and fixed relation to the car body will serve the purpose.

For the purpose of adjusting the car body on its central axis so that the groove of the sheave will keep on a plane in direct line 55 of the force by means of which the car is

moved, outriggers with appropriate bearings are placed at or near the end of the car toward which the engine is located. By this arrangement while the cable is taut under stress of a load it cleanly feeds into 60 the groove of the sheave without bending at the outrigger.

This arrangement of parts and members gives opportunity to the builder to accomplish great strength and durability of all 65 parts without the unnecessary use of steel or other material. The cable while resting on the rim of the sheave accomplishes the necessary curve of one hundred and eighty degrees without subjection to the deteriorat- 70 ing effect of external strain combined with bending or internal strain to which wear is chiefly attributable.

The loaded vehicles are attached to this special car by means of couplers preferably 75 of automatic type.

The accompanying drawings and the following specification suggest a type of construction which will accomplish the useful purposes attained by our invention, but it is so understood that the manner of construction and forms of the various members constituting the completed machine are subject to much variation.

In the drawings Figure 1 is a perspective 85 view showing the front and side of this car.

Fig. 2 is a perspective view showing one side and the rear of the same.

Fig. 3 is a plan view of this car.

Fig. 4 is a side elevation of the same.

Fig. 5 is a front end view of the same.

Fig. 6 is a rear end view with the rear pony truck omitted to better illustrate the center truck.

Fig. 7 is a sectional view on broken line 95 7-7 of Fig. 3 showing the rear end of the car.

Fig. 8 is a fragmentary view partly in section and partly in elevation showing parts of the truck frame and center truck bolster. 100

Fig. 9 is a view in side elevation of a form of cable guide used for guiding the cable around a curve.

Fig. 10 is a diagrammatic plan view showing an application of my invention to an inclined logging road. 105

Fig. 11 is a similar diagrammatic view in side elevation.

Like reference numerals designate like parts throughout the several views. 110

In logging heavy timber it is often desirable to log on hillsides and at relatively high elevations where the logs must be transported down relatively steep inclines the 5 grades of these inclines running as high as fifty per cent, and said inclines being much too steep to permit the use of ordinary logging locomotives thereon. This condition has developed the use of a system of logging 10 in which logging railroads are built in as nearly a straight line as possible down these inclines and logging cars loaded with logs are lowered down these inclined railroads by the use of power units, termed snubbing 15 engines, located along these inclines usually toward the upper end, and two part cables operated by the snubbing engines. In connection with this apparatus it has been found necessary to use a specially constructed 20 car which is operated by the two part hauling cable and which may be connected with other load carrying cars that are to be moved up or down the incline railroads. These cars, commonly termed lowering cars, 25 are of very strong and heavy construction and must be provided with means, as a sheave, around which a hauling cable may pass to govern the movement of the car on the inclined railroad. This hauling cable 30 is ordinarily double or what is termed a two part cable and may be several miles in length, one part of said cable lying on one side of the railroad track and the other part of said cable lying on the other side of the 35 railroad track, the sheave in the lowering car operating in the bight of the cable, the cable on one side being movable and the cable on the other side being at rest, one end of the cable being secured to the winding 40 drum of a snubbing engine at one side of the track and the other end being securely anchored near the snubbing engine at the other side of the track. The cables are expensive and it is very desirable to conserve 45 and prolong the life of the same. The connection of the cable as hereinbefore described gives a one to two reduction in speed and a substantially two to one mechanical advantage between the engine and car respectively. 50 The loads on trailers handled by a lowering car of this nature are necessarily very heavy, the railroad tracks over which the cars operate are often sharply curved and have intersecting laterals or branches and 55 the grade of said tracks often changes abruptly, thereby necessitating a car of very strong and substantial construction, heavy weight and relatively great flexibility to compensate for curves and changes of grade 60 in the track.

We secure this flexibility in a heavy car of this nature by mounting the car frame on a main truck disposed at or near the center of said car frame and on two pony trucks 65 disposed near the two ends of the car frame

and arranged to permit the car frame to tilt vertically and to swing sidewise relative to said trucks.

Referring specifically to the drawings we provide a truck frame, preferably but not necessarily of fabricated steel construction made up of a lower rectangular frame portion 15, a transverse support 16 near the front end of frame 15 and projecting beyond the sides of the same and a longitudinally extending medially disposed beam 17 spaced above the lower frame portion 15 and constituting an upper frame portion. The front end of beam 17 is secured to the transverse support 16 and the rear end of beam 17 is supported by a very substantial structure 18 built upon frame 15. A brace and reinforcing plate 19 is provided on the top of transverse support 16 and upper frame beam 17.

The car frame is supported on three railroad trucks designated generally by the numerals 20, 21 and 22, the center truck 20 being a main supporting or carrying truck and the end trucks being flexibly mounted 90 guide trucks of the form commonly known as pony trucks.

The center truck 20 is provided with the usual yieldingly mounted bolster member 23, resting on springs 24. A crowned bearing plate 25, Fig. 8, is secured to the top of bolster member 23 mid way between the two ends and is provided with an upwardly protruding pivot stud 26, Figs. 7 and 8, that fits into a hole in a bearing plate 27 on the bottom of lower car frame 15 thereby forming a pivot joint that admits of a limited amount of rocking or tilting movement of the car frame relative to this truck. A slight rolling movement of bolster 23 on springs 24 is permitted thus increasing the tilting movement afforded longitudinally of the car. The center truck 20 is disposed under or near the center of the car and is arranged to carry substantially the entire 100 weight of the car.

A bearing 28 for the lower end of an upright shaft 30 is supported on the plate 27 and on channel members 31 that extend crosswise of lower frame 15 and another bearing member 32 for the upper end of shaft 30 is supported by upper frame beam 17.

A relatively large sheave 33 preferably of built up steel construction having a sectional periphery or rim and a fabricated center is secured by plate 29 to shaft 28 and rotatably disposed between lower frame 15 and upper frame beam 17. A thrust plate 34 on bearing 28 supports the 120 weight of sheave 33. Rollers 35 are provided below the periphery of sheave 33 at a plurality of points to relieve the shaft 30 and bearing 28 and 32 of excess strain. Sheave 33 has a groove 39 for the reception 125 130

of a hauling cable 36, one end of which may be secured to a winding drum 37 on a snubbing engine 38 and the other end of which may be anchored to a fixed support 40 near 5 the snubbing engine.

By the use of the single sheave 33 of maximum diameter, the direction of the cable 36 is changed 180 degrees with the least possible bending and the strain on that part of 10 the cable that is drawn around the sheave is greatly reduced due to the long arc of contact on the sheave thereby relieving fatigue in the cable momentarily during the time it is passing around the sheave and is 15 subjected to bending strains and greatly prolonging the useful life of the cable.

Guide rollers 41, 42 and 43 for the cable 36 are provided in both ends of transverse support 16 in alignment with the side ext- 20 tremities of sheave 33, the rollers 41 and 42 being below and above the cable 36 respectively and the rollers 43 occurring in pairs one on each side of the cable 36. These 25 guide rollers adjust the car body so that sheave 33 is always in the plane of the line of pull of the cable thereby avoiding bending of the cable.

The pony trucks each embody an axle 44 having wheels 45 and journaled in bearing boxes 46 upon which springs 47 are supported. A transverse truss or bolster member 48 preferably formed of two spaced apart bars has its two ends suspended from the ends of the springs 47 by links 50 so 35 that it is free to move vertically a limited amount and is also free to move forwardly and rearwardly a limited amount relative to the wheels and axle. A bolster block 51 is disposed between the two members of bolster 40 48 and suspended therefrom by links 52 so that it is free to swing sidewise of the pony truck. The upper portion of the bolster block 51 has a relatively deep socket 53 for the reception of a relatively long hub 54 on 45 a plate 55 that is secured to and supports the end of the car frame. A king pin 56 connects bolster block 51 and hub portion 54 of plate 55, said king pin being relatively long and having a cross key 56' which permits hub 54 to move upwardly a considerable distance in socket 53 thus allowing the end of the car frame to be raised without lifting the wheels of the truck off of the railroad track 57 on which they run. A truss member 58 extending rearwardly in the case of the front pony truck and forwardly in the case of the rear pony truck connects said pony trucks with the car frame and radius rods 60 extend from the forward ends of 50 the truss members to the lower parts of the bearing boxes 46 of the trucks.

The pony trucks make possible both vertical and sidewise movement of the ends of the car without lifting or forcing the truck 55 wheels off of the track thus making it pos-

sible for the truck wheels to follow the rails around a curve or over a change in grade while the cable holds the car frame in substantially its previous alignment. The variations in the angular position of the car 70 frame due to changes in grade are not great but it is necessary that these changes be compensated for, to keep the sheave 33 always in line with the line of pull of the cable and thereby prevent excessive wear of 75 the cable.

The car frame is provided at the rear end with a coupler 61 secured by a vertical pin 62 to a draw bar 63 that is secured by horizontal pivot pin 64 to the frame. The coupler 61 is of substantially the usual standard shape except that it is provided with a rigid integral hook portion or lip 65 for engagement with the pivotally connected hook portion of the usual coupler member and is 80 further provided with an integral bottom 66 which will prevent the coupler member that fits thereinto from dropping out at the bottom in case the end of the lowering car is raised as in passing over abrupt changes 85 in grade. The coupler 61 is also substantially twice the depth of the ordinary coupler so that the members with which it is engaged can not move upwardly out of engagement with said coupler 61. This coupler 90 is a great advantage to a car of this nature and saves considerable time and labor over present methods which usually employ manually operated flexible coupling members to connect the logging cars to the low- 95 ering cars.

The hauling cable 36 is supported on rollers 67 that are arranged along side of the track. In depressions and at grade changes where there is a tendency for the cable to 100 be raised, the rollers are provided in inverted position above the cable to hold the same down. Brackets instead of rollers may be provided on the dead line side of the track if desired.

In Figure 9 we have shown a cable guide of the form used in guiding the cable around curves in the track. This device comprises a bell crank shaped bracket mounted on a pivot 70 and provided with two arms 71 and 72 arranged at substantially right angles to each other. A roller 73 is journaled on the arm 71. These devices are mounted on rigid supports alongside of the track at the location of the curves and are normally arranged 110 to assume the positions shown by full lines in Fig. 9. As the lowering car moves down the inclines the transverse support 16 will engage and depress the upwardly protruding arms 72 thereby raising the rollers 73 behind support 16 into a suitable position for the cable to be drawn over the rollers 73. The rollers 73 will remain raised until they are engaged by the transverse support 16 and lowered upon the return of the lowering 120 125 130

car. On the side of the track where the hauling cable 36 is at rest the rollers 73 may be omitted and the bell crank arm 71 may be shaped to form a guide for the dead portion 5 of the cable instead of forming a bearing for a roller 73.

In operation this lowering car is lowered down or drawn up the inclined trackway by 10 unwinding or winding in the hauling cable 36 and serves as a means of hauling the cars that are coupled thereto. The inclined trackway, necessarily under practical working conditions, has numerous changes in 15 grade and usually has curves or has lateral intersecting trackways or branches 74 which constitute curves over which the hauling car must pass. In Fig. 11, we have shown the hauling car at the location of a break in the grade. At this point the hauling cable 20 tends to prevent any changes in the angular position of the car frame and the rear pony trucks must drop in order to run upon and follow the track. After the lowering car has passed the point where the grade changes 25 the cable guides will cause the cable to again exert a straight pull and the pony trucks will resume their normal position. In passing around a curve in the track the cable holds the car frame substantially in alignment 30 with the line of pull but the car trucks must all follow the rails. The vertical and horizontal movement allowed by the pony trucks permits them to swing in any direction 35 from their normal position under the car frame in following over or around a curve in the track. The universal movement afforded by the pony trucks also allows them to follow a curve and pass over a change in grade at the same time, if necessary, 40 while the car frame is held in alignment with the line of pull of the hauling cable.

From the preceding description it will be seen that the pony trucks in this structure 45 afford a flexibility which is very desirable in a lowering car of this nature and which permits the car frame to be moved either horizontally or vertically or both while the trucks remain firmly and securely on the track. This flexibility is highly desirable 50 on tracks where there are sharp curves and breaks in grade.

The cable 36 always draws squarely into the groove of the sheave 33 without rolling 55 or sliding on said sheave and makes continuous contact with the sheave through an arc of substantially one hundred and eighty degrees thereby avoiding as far as possible all sharp bending and excessive wear of the cable. The single sheave gives the full 60 spread of line required for operating and clearance purposes and also gives the maximum bending arc of the cable that it is possible to obtain for a given spread.

65 If desired a hand rail 29 may be provided

on the car frame. This hand rail is shown in Figs. 4, 5 and 7 but is omitted in the other views.

The foregoing description and accompanying drawings clearly disclose a preferred embodiment of our invention but it will be understood that this disclosure is merely illustrative and that numerous changes may be made within the scope and spirit of the following claims. 75

We claim:

1. A car for use on an incline track with horizontal or vertical curvature moved by a cable actuated by an engine and held by appropriate means in approximately parallel relation to the rails of the track, passing around a single revolving sheave fixedly mounted on the car to which burden bearing trucks and vehicles may be coupled with means whereby the car will adjust itself so that the sheave thereon carrying the cable will be in a plane with the lines of force which move the car, without substantial bending of the cable before and after it enters and leaves the sheave. 90

2. A car for use on an incline track with horizontal or vertical curvature moved by a cable actuated by an engine and held by appropriate means in approximately parallel relation to the rails of the track, passing around a single revolving sheave fixedly mounted on the car to which burden-bearing trucks and vehicles may be coupled with means whereby the car will adjust itself so that the sheave thereon carrying the cable will be in a plane with the lines of force which move the car, without substantial bending of the cable before and after it enters and leaves the sheave, with means for keeping the car on the track when passing over curves. 95

3. A car for use on an incline track with horizontal or vertical curvature moved by a cable actuated by an engine and held by appropriate means in approximately parallel relation to the rails of the track, passing around a single revolving sheave of sufficient diameter to carry without other means the cable outside the rails of the track, fixedly mounted on the car to which burden-bearing trucks and vehicles may be coupled with means whereby the car will adjust itself so that the sheave thereon carrying the cable will be in a plane with the lines of force which move the car, without substantial bending of the cable before and after it enters and leaves the sheave. 110

4. A car for use on an incline track with horizontal or vertical curvature moved by a cable actuated by an engine and held by appropriate means in approximately parallel relation to the rails of the track, passing around a single revolving sheave of sufficient diameter to carry without other means the cable outside the rails of the track, fixedly 115 120 125 130

- mounted on the car to which burden-bearing trucks and vehicles may be coupled with means whereby the car will adjust itself so that the sheave thereon carrying the cable 5 will be in a plane with the lines of force which move the car, without substantial bending of the cable before and after it enters and leaves the sheave, with means for keeping the car on the track when passing 10 over curves.
5. A cable operated lowering car embodying a car frame, a main load supporting truck at the center of said car frame, other trucks flexibly supporting the ends of said 15 car frame and a single large sheave mounted on said car frame parallel therewith for the reception of a hauling cable, said single sheave affording sufficient spread of the hauling cable for clearance purposes.
- 20 6. A cable operated lowering car embodying a car frame, a main truck and two pony trucks flexibly and adjustably supporting said car frame for movement over an inclined trackway and sheave means mounted 25 on said car frame and arranged to run in the bight of a hauling cable, the plane of said sheave means being constant relative to the plane of said car frame, and the flexibility afforded to said car frame by said 30 pony trucks permitting automatic adjustment of said sheave means into the plane of the line of pull of said hauling cable.
7. A car of the class described embodying a car frame, a main load supporting truck, 35 means including a pivotal rocker bearing for supporting said car frame on said truck, a pony truck flexibly supporting each end of said car frame and a sheave rotatably mounted on said car frame parallel therewith for the reception of a hauling cable.
- 40 8. A cable operated lowering car embodying a car frame, car trucks supporting said car frame, a single sheave of large diameter mounted for rotation on said car frame parallel therewith and a double hauling cable having continuous contact with said sheave for an angle of substantially one hundred eighty degrees, said sheave maintaining sufficient spread of said hauling cable for clearance purposes.
- 50 9. A cable operated car embodying a truck supported car frame, and a single sheave rotatably mounted on said car frame parallel therewith and overhanging both sides of said car frame.
- 55 10. A cable operated car embodying a car frame, a main center truck and two pony trucks flexibly and adjustably supporting said car frame for movement over an inclined track and a relatively large sheave 60 rotatably mounted on said car frame on an axis perpendicular thereto and projecting beyond opposite sides of said car frame.
- 65 11. A cable operated lowering car embodying a car frame, a main truck at the center of said car frame, a pony truck at each end of said car frame, a relatively large sheave disposed parallel with said car frame and projecting beyond the opposite sides thereof and rotatable on an axis that 70 is perpendicular to said car frame, and a hauling cable passing around said sheave, one end of said cable being permanently anchored and the other end of said hauling cable being connected with a power operated 75 winding drum.
12. A cable operated lowering car embodying a lower car frame structure, an upper car frame structure rigid with said lower car frame structure and spaced therefrom, a relatively large sheave rotatably mounted between said two car frame structures for the reception of a hauling cable and car trucks supporting said car frame structure for movement over a railroad 80 track.
13. A cable operated lowering car embodying railroad trucks, a lower car frame structure supported on said trucks, an upper car frame structure rigid with said lower 85 car frame structure and spaced therefrom, a sheave disposed between said two car frame structures and a bearing axle for said sheave perpendicular to said two car frame structures and supported in both of said 90 car frame structures.
14. A cable operated lowering car embodying a car frame, trucks supporting said car frame, a sheave rotatably mounted on said car frame parallel therewith and 100 projecting beyond the edges of said car frame, a support extending crosswise of said car frame in front of said sheave, guide rollers in said support in alignment with the side extremities of said sheave and a 105 hauling cable passing around said sheave and through said guide rollers.
15. A lowering car of the class described embodying car trucks, two relatively rigid car frame structures supported on said 110 trucks in spaced apart relation one above the other, a single sheave of large diameter rotatably mounted between said car frame structures parallel therewith and projecting beyond the sides of said car frame 115 structures, a rigid support arranged crosswise of said car frame structures in front of said sheave, guide rollers in said support in alignment with the side extremities of said sheave and a hauling cable passing around 120 said sheave and through said guide rollers.
16. In a lowering car of the class described a wheel supported car frame and a relatively large sheave arranged to be rotatably mounted on said car frame for receiving a hauling cable said sheave having a grooved peripheral portion formed of a plurality of sections and a central portion of fabricated steel.
17. In a lowering car a wheel supported 130

car frame, sheave means on said car frame arranged to run in the bight of a hauling cable and a coupler on one end of said car frame arranged to engage with a standard 5 coupler on a logging car said coupler having a solid hook portion arranged to engage with the pivoted hook portion of the standard coupler and having a closed bottom end

and being of substantially twice the depth of the standard coupler. 10

The foregoing specification signed at Tacoma, Washington, this 28th day of October, nineteen hundred twenty-four.

HERMAN POTRAFKE.
ROY N. ALLEN.
